Vearl S. Wince, Newark, Ohio, assignor to Holophane
Company, Inc., New York, N.Y., a corporation of
Delaware

Original design application May 19, 1967, Ser. No.
7,190. Divided and this application Feb. 19, 1968,
Ser. No. 13,407

Term of patent 14 years

Int. Cl. D26—03

U.S. Cl. D48—23

FIG. 1 is a bottom perspective view of a luminaire showing the new design; and

FIGS. 2, 3 and 4 are respectively side, bottom and end views of the luminaire according to FIG. 1.

The lens portion is shown in broken lines in FIGS. 1 and 2 for illustrative purposes only. The dominant features of my design reside in the portions shown in full lines.

This application is a division of copending application Ser. No. D. 7,190, filed May 19, 1967, and entitled "Luminaire."

I claim:

The ornamental design for a luminaire, as shown and described.
